ADJUSTABLE INFANT'S CHAIR

Clarence O. Hamilton II, Columbus, Ind., Robert C. Winters, Ridgefield, and Raymond R. Spilman, Stamford, Conn., assignors to Hamilton Cosco, Inc., Columbus, Ind., a corporation of Indiana

Filed Apr. 18, 1968, Ser. No. 11,514

Term of patent 14 years

Int. Cl. D6—01

U.S. Cl. D15—1

Fig. 1

Fig. 3

Fig. 2

Fig. 4

Fig. 5

FIG. 1 is a front elevation showing our design;
FIG. 2 is a top plan view thereof;
FIG. 3 is a rear elevation thereof;
FIG. 4 is a side elevation thereof; and
FIG. 5 is a side elevation thereof similar to FIG. 4, but
showing the chair in a different position of adjustment.

We claim:
The ornamental design for an adjustable infant's chair,
as shown.
